UNITED STATES PATENT OFFICE.

AUGUSTO RICHARD, OF MILAN, ITALY.

INSULATOR.

No. 821,746.

Specification of Letters Patent.

Patented May 29, 1906.

Application filed March 17, 1904. Serial No. 198,626.

To all whom it may concern:

Be it known that I, AUGUSTO RICHARD, manager of the firm trading under the name of Societa Ceramica Richard-Ginori, a citizen 5 of the Republic of Switzerland, residing at 115-117 San Cristoforo, Milan, Italy, have invented certain new and useful Improvements in Insulators; and I do hereby declare the following to be a full, clear, and exact description 10 of the invention, such as will enable others skilled in the art to which it appertains to make and use the same.

The present invention refers to means for supporting insulators for overhead electric 15 lines of high voltage and fixing the same on the pins or stems which are intended to support said lines.

The pins heretofore in use for the suspension 20 of overhead lines are made either of wood or iron or a combination of these two materials; but they are solid all through. As the weight of said pins must be contained within reasonable limits, solid pins or stems are scarcely able to resist the strain which 25 they are to stand without showing a deflection, which is highly noxious, as it gives rise to the breakage of numerous insulators made, as they are, of more or less brittle material— porcelain, glass, stoneware, or the like.

30 In order to obtain for the cross-section of the suspension-pins a modulus the high value of which enables them to resist the greatest bending moment to which they may be subjected, I adopt hollow or tubular pins 35 of iron, steel, or any appropriate metal. By the adoption of hollow pins I am enabled to concentrate the weight by increasing the thickness of the tubular wall just in the points where the pins are to stand the greatest 40 strain, this result being attained without exceedingly increasing their total weight.

When using hollow pins, the modulus of the section is double that of solid pins for the same weight of metal, and more than two- 45 thirds of the insulator breakages usually occurring are thereby avoided. When it is desired to prevent the atmospheric wetness to condense within the cavity of the pins, they may be filled with tarry substances, powdered 50 gravel, or other mineral powders.

It is well known how difficult it is to fix the insulators made of brittle material upon the metallic pin, either hollow or solid. In order to avoid or limit the breakages, which 55 occur oftener with large high-voltage insulators that are subjected to heavy strains

while being secured in place, a layer of soft material is inserted between the insulator and the metallic pin. The soft materials usually employed to that effect consist of 60 hemp, flax, jute, or cotton filaments impregnated with oily or fatty substances, sulfur, and quickly-drying cements of various descriptions. The employment of each of these substances is connected with many inconveniences. Some of them swell and cause the insulators to crack, other ones cannot withstand the inclemency of the weather, while the best cements stick so fast that the insulator cannot be removed without going to 70 pieces. Moreover, the employment of any of the above means renders the mounting of the insulators very long, costly, and wearisome, so much the more that said mounting must take place just at the moment when the 75 suspension-poles are being erected—that is to say, under often unfavorable conditions.

All said inconveniences are removed according to the present invention, which consists in securing to the inside of the insulator 80 a thin metal bush made to adhere thereto by a thin lining of an appropriate cement. Said operation may be carried out at the same works where the insulators are manufactured, thus putting on the market insulators which are ready for being screwed or otherwise secured upon their supports without any previous troublesome operation being required. Should the insulators be intended for employment on low-voltage lines, 90 bushes made of compressed paper, cork, wood, or other appropriate materials may be employed instead of the metal bushes hereinabove described.

The annexed drawing shows, by way of example, a vertical section of an overhead-line suspension-pole made according to my invention on which an insulator is secured by the means which also form the object of the present invention.

In said drawing, *a* is the tubular pin, which is supposed to be of iron or steel and to taper toward the top. It is secured to the wood bracket *c* by means of the nut *d* and the iron washers *f*. The shell *g*, surrounding the pipe *a* 105 and made of the same material (glass, porcelain, or stoneware) as the insulator proper, *j*, rests upon a washer of tarred pasteboard *h*, the interval between the inside wall of the shell *g* and the outer wall of the iron pipe *a* 110 being filled with concrete *b*.

The insulator proper, *j*, lined internally with

a thin layer of cement *e*, to which a brass bush *i* adheres, is screwed upon the top of the hollow tube *a*, properly threaded to that effect, a washer of pasteboard *k*, impregnated with paraffin, being conveniently inserted between the insulator proper, *j*, and the porcelain, glass, or stoneware shell *g*.

The means by which the metal bush *i* is secured to the inside cavity of the insulator 10 and the means by which the insulator is fixed on the top of pin *a*—namely, screw-threads, ribs, lugs, projections on one side, slots, notches, grooves on the other side, cements or glues of whatever description—may vary 15 in whatever convenient manner, and the form of bush *i* may vary accordingly without departing from the principle of the invention.

What I claim, and desire to protect by Letters Patent, is—

1. An insulator having a cup-shaped me-

tallic bush having its inner end closed, a thin layer of cement securing the bush to the insulator, and a paraffined washer surrounding and abutting the bush to prevent the entrance of moisture to the cement. 25

2. The combination with the metallic post having a screw-threaded upper end, of a shell surrounding the post, below the top thereof, an insulator having a metallic bush, cemented therein, to engage the post, and a paraffined washer interposed between the shell and the insulator and preventing the entrance of moisture to the cement securing the bush. 30

In testimony whereof I have affixed my signature to this specification in the presence of two witnesses. 35

AUGUSTO RICHARD.
